W. R. FLETCHER

BLAST TUBE FOR MACHINE GUNS

Filed April 18, 1922

W. R. Fletcher Inventor

Robert N. Young Attorney

UNITED STATES PATENT OFFICE.

WALLACE R. FLETCHER, OF DAYTON, OHIO.

BLAST TUBE FOR MACHINE GUNS.

Application filed April 18, 1922. Serial No. 555,269.

To all whom it may concern:

Be it known that I, WALLACE R. FLETCHER, a citizen of the United States, residing at Dayton, in the county of Montgomery and 5 State of Ohio, have invented certain new and useful Improvements in Blast Tubes for Machine Guns (Case A), of which the following is a specification.

My invention relates to a blast tube for 10 machine guns. The purpose of such a tube is to convey the blast or flash from the muzzle of the gun forward through any section or past any material or equipment which it is necessary to protect against fire 15 or blast effect.

It is particularly important to protect 20 parts of airplanes from exposure to fire and blast effect of the machine guns mounted thereon. In a fixed gun mount the machine gun is usually placed so far to the rear that the muzzle does not project through the cowl of the airplane and it becomes one of the functions of the blast tube to carry the 25 gases of the machine gun forward through the cowl.

The main objects of my invention are to 30 provide a blast tube of simple and sturdy construction which can be easily applied in firm relation to the machine gun.

35 By using a tube of my improved construction in a gun which fires between the propeller blades, the hot gases and flame are carried forwardly past the propeller blade, before the blade has revolved far enough to be in the line of fire.

For illustrative purposes the specification 40 describes, and the accompanying drawings show the invention applied to the type of gun known as the Vickers aircraft machine gun.

In the drawings:

Figure 1 is a side elevation of the blast 45 tube and part of a machine gun to which it is applied;

Figure 2 is a sectional view on the line 2-2 of Fig. 1 and

Figure 3 is a detail sectional view showing 50 the relation between the muzzle attachment and blast tube.

The numeral 10 designates a barrel jacket 55 which is preferably a corrugated cylinder, formed from drawn-steel tubing and ventilated near both its forward and rear ends to permit free circulation of air around the

barrel 11, the forward vents being indicated at 12. The barrel jacket cap 13, is a steel

forging and closes the forward end of the barrel jacket, except for ventilating holes formed therein. A stuffing box 14 and follower 15 are screwed in the rear and front 60 respectively of a cylindrical opening 16 formed through the face of the jacket cap 13 at the lower portion thereof. The stuffing box flares outwardly toward the rear in order to act as a guide in assembling the 65 barrel. The follower is provided with an inner annular flange 17 of reduced diameter which screws into the opening 16 and with an outer annular flange 18 having several holes 19 therein. A cylindrical sleeve 20 is 70 connected to the flange 18 by annular interrupted rings 21 and is formed with a hole adapted to register with one of the holes 19 for receiving a split locking pin 22. For convenience the pin 22 is carried at one end 75 of a chain 23, the other end of which is provided with an S-hook engaging an eye bolt 24 secured to the barrel jacket cap 13. The sleeve 20 projects forwardly of the flange 18 and is formed with an annular row of apertures 25 through which the explosion gases 80 may have a restricted flow. The forward end of the sleeve 20 is closed, except for the axial passage allowing escape of the bullet, by the front disk 26 which is screwed in 85 place. The forward end of the gun barrel 11 has detachably secured thereto a disk 27. The device comprising the follower, sleeve and front disk is termed a muzzle attachment and its function is to increase the recoil 90 action of the barrel. The bullet when fired causes a recoil of the gun barrel and the attached disc 27 relatively to the rest of the gun. This recoil action is assisted by the gases issuing from the gun barrel and flowing into the chamber between disc 27 and disc 26, thus creating a pressure helping the recoil of the gun barrel. As soon as the recoil has taken place some of the gases in this chamber will pass out through the openings 95 25 which will have been uncovered and communicate with the chamber when the barrel has recoiled. The openings 25 conduct the gases to the rear part of the blast tube. It will be understood that the particular 100 form of muzzle attachment has been described for illustrative purposes only and that my invention may be applied to muzzle attachments of different form and construction.

According to my invention a tube 30 is of 105 such diameter at one end 31 as to fit snugly

- 2 over the sleeve 20. This portion of the tube is provided with an opening adapted to register with a like hole in the sleeve and one of the holes 19 for the purpose of receiving pin 22 which thus locks the blast tube in position. The tube 30 is formed with an enlarged section 32 which extends around the sleeve 20 at the apertures 25 in order to provide a chamber 33 for receiving the explosion gases issuing through said apertures. This enlarged section is preferably welded to the forward body portion of the tube 30 and the end piece 31 at the tapered and abrupt shoulders 34, 35 respectively. The body 15 portion of the tube in front of the shoulder 34 extends forwardly sufficient to protect the parts of the airplane or its equipment from exposure to fire and blast effect. The end piece 31 by tightly engaging the sleeve of 20 the muzzle attachment insures against any leakage of flame or blast except through the forward open end of the blast tube.
- The explosion gases issuing through the restricted apertures 25 are received in chamber 33 and are conveyed from thence through the tube to the open end thereof. The removable pin 22 prevents forward and backward movement of the blast tube with relation to the muzzle attachment.
- 30 I claim:
1. A device adapted to be attached to the forward end of a machine gun to carry the flash rapidly forwardly, consisting of a cylindrical tubular part open at its front end and extending from a point near the end of the gun barrel to a point considerably for- 40 ward of the same, said part being considerably larger than the bore of the gun, and an enlarged rear part adapted to be connected to the forward end of the gun and supporting said cylindrical tubular part.
  2. A blast tube adapted to be attached to the forward end of a machine gun to carry the flash rapidly forwardly consisting of a cylindrical tubular part free from internal 45 obstructions, open at its front end and extending from a point near the gun muzzle to a point considerably forward of the same, said part being considerably larger than the bore of the gun and an enlarged rear part 50 adapted to be connected to the forward end of the gun and supporting said cylindrical tubular part, said enlarged rear part adapted to communicate with a recoil muzzle attachment to carry the gases from the same 55 to the forward cylindrical tubular part, the opening at the front end of the forward cylindrical part providing the only exit for the gases from the blast tube.
  3. The combination with a muzzle attachment for a machine gun having a series of apertures formed therein, a blast tube having a portion thereof mounted on said muzzle attachment and being provided with an aperture for alignment with one of said apertures in said muzzle attachment, and means passing through said aligned apertures to retain said tube and said muzzle attachment in operative position.

In testimony whereof I affix my signature.

WALLACE R. FLETCHER.
